UNITED STATES PATENT OFFICE.

MICHAEL WISEMAN, OF SOUTH BOSTON, MASSACHUSETTS.

FLUE CLEANER.

Application filed June 4, 1923. Serial No. 643,254.

To all whom it may concern:

Be it known that I, MICHAEL WISEMAN, a citizen of the United States, and resident of South Boston, county of Suffolk, State of Massachusetts, have invented an Improvement in Flue Cleaners, of which the following description, in connection with the accompanying drawing, is a specification, like characters on the drawing representing like parts.

This invention relates to a flue cleaner of the type having arms for engaging the walls of the flue and cutting the incrustation therefrom and the general object thereof is to provide such a flue cleaner which has a guiding portion for centering the cleaner within the flue and which has the parts so arranged that the cleaner will not stick in the flue.

In flue cleaners of this general type a plurality of arms radiates from a central shaft or bar and cut the incrustation from the walls of the flue both on the forward and on the rearward stroke of the cleaner. With this construction, however, the rear arms are quite likely to engage with the portions of the incrustation which can not be easily dislodged or should the head of the cleaner be accidentally forced entirely through the flue and into the steam space between the end of the flue and the wall of the boiler, the rear arms catch over the inner end of the tube with the result that the cleaner can not be removed therefrom. In the flue cleaner which forms the subject matter of my invention I provide the cleaner with rearwardly extending portions which embrace the bar at their ends so that the cleaner does not stick in the flue and bulge between their ends and the point at which they are fastened to the bar to form a guide to center the cleaner within the flue. I also form shoulders on the bar adjacent which lie the ends of the rearwardly extending portions of the cleaner thus forming a smooth surface leading up to the bulge to prevent the cleaner sticking within the flue.

Other objects and features of the invention will be more fully hereinafter set forth.

In order to give an understanding of the invention I have illustrated in the drawings a selected embodiment thereof which will now be described, after which the novel fea-

tures will be pointed out in the appended claims.

In the drawings:

Fig. 1 is an elevation of the cleaner with in the flue, the flue being shown in section;

Fig. 2 is a section through the cleaner and flue on the line 2—2, Fig. 1;

Fig. 3 is a section on the line 3—3, Fig. 2;

Fig. 4 is a section of a portion of the cleaner showing one way in which the parts may be arranged to give a smooth surface leading from the bar up to the cleaner.

As illustrated herein the flue cleaner which forms the subject matter of the present invention is provided with a body comprising a body bar 1 on which are mounted spring arms 2 presenting flared forwardly 70 extending portions 3 having sharpened scraping edges 4 for engaging the walls of the flue 5 and cutting the incrustation therefrom. For centering the cleaner within the flue the spring arms have rearwardly extending portions 6 embracing the body bar 1 at their ends 7 and bulging at 8 between the ends 7 and the point 9 at which the arms are fastened to the bar. To enable the cleaner to be used in long flues an extention bar 10 75 may be fastened to the body bar 1. The sides of the bulging portions are spaced slightly from the walls of the flue but are close enough thereto to form a guide for the cleaner when inserted in the flue. The desirability of the guiding effect of the bulging portions is very apparent when the cleaner is just being started in a flue or is used to clean a long flue in which, when the body of the cleaner is near the inner end of the 80 flue and the extention bar 10 bends under its weight to force the upper scraping edges against the wall of the flue, the bulging portions rest on the bottom of the flue to prevent the scraping edges being presented to the wall of the flue at such an angle that they cut into the wall.

In Fig. 4 the body bar is shown with shoulders 11 formed thereon and the ends 7 of the rearwardly extending portions of the spring arms are situated adjacent the shoulders to form a smooth surface leading up to the bulge to prevent the cleaner sticking within the flue. This feature is particularly desirable should the body of the 105 cleaner go entirely through the flue and into

the space between the inner end of the flue and the wall of the boiler, as it prevents the cleaner from getting caught on the inner end of the flue and facilitates the withdrawal of the cleaner.

5 The spring arms may be mounted on the bar in any suitable manner but preferably by means of bolts 12 which extend through said bar and through the opposite spring 10 arms.

The body bar has a head 13 at its forward end which assists in pushing ahead of the cleaner the scale which is dislodged from the wall of the flue by the scraping 15 edges 4, and has at the rear end means for interlocking with the extension bar. Although the two bars may be interlocked in any suitable manner I prefer to cut the body bar and extension bar part way 20 through and provide the ends of the bars with bevelled faces 14 and 15 extending entirely across the bars to hold them in line. The bars are held together by means of a bolt 16. The interlocking portions of both 25 bars bulge as shown at 17, Fig. 1, so that should the head of the bar and the interlocking portion both pass the inner end of the flue the entire assembly of the cleaner and the extension bar may be turned sideways 30 so that the bulge portion will ride over the inner end of the flue and prevent the cleaner from sticking in the flue by the bolt 16 catching on the inner end of the flue.

The flue cleaner and extension bar may 35 be made of any suitable material but I prefer to make both the body bar and the extension bar of a cheap but strong grade of iron and the spring arms of a metal such as steel which has a spring to it but which 40 will retain a sharp edge on the scraping edges although the cleaner is subjected to rough use. The entire assembly must be of

rugged construction and may be made in different sizes according to the size of the flues in which the cleaners are to be used. 45

Although some particular and preferred forms of construction have been described modifications may be made and the invention is to be construed as broadly as the limitations in the claims, taken in conjunction with the prior art, may allow. 50

Having thus described the invention what is claimed as new and desired to be secured by Letters Patent is:

1. A flue cleaner comprising a bar, spring 55 arms mounted on the bar presenting flared forwardly extending portions having sharpened scraping edges for engaging the walls of the flue and cutting the incrustation therefrom, and rearwardly extending portions embracing the bar at their ends and bulging between the ends and the point at which the arms are fastened to the bar to form a guide for the cleaner when inserted in the flue. 60

2. A flue cleaner provided with a body comprising a body bar with a head at one end and means at the other end for interlocking with an extension bar, spring arms mounted on the bar presenting flared portions extending beyond the enlarged head having sharpened scraping edges for engaging the walls of the flue and cutting the incrustation therefrom, and rearwardly extending portions embracing the shaft at 75 their ends and bulging between the ends and the point at which the arms are fastened to the bar to form a guide for the cleaner when inserted in the flue, and an extension bar to interlock with the body bar to provide a 80 handle for the cleaner.

In testimony whereof, I have signed my name to this specification.

MICHAEL WISEMAN.
